UNITED STATES PATENT OFFICE.

EDWARD A. HERR, OF PHILADELPHIA, PENNSYLVANIA.

STORM-APRON ATTACHMENT.

No. 907,708.

Specification of Letters Patent.

Patented Dec. 22, 1908.

Application filed February 1, 1908. Serial No. 413,847.

To all whom it may concern:

Be it known that I, EDWARD A. HERR, a citizen of the United States, residing at Philadelphia, Pennsylvania, have invented 5 certain new and useful Improvements in Storm-Apron Attachments, of which the following is a specification.

My invention relates to supports for storm aprons or shields of vehicles, and consists of 10 supporting rails fixedly connected beneath the hood, and two connections between the apron and the said rails, both the said connections sliding on the rails and one constituting a permanent connection between the 15 apron and its rail and the other detachable, with means for supporting the apron when rolled in position at one side of the vehicle, as fully set forth hereinafter and as illustrated in the accompanying drawing, in 20 which—

Figure 1 is a perspective elevation of the vehicle and apron with my improved connecting means; Fig. 2 is a longitudinal sectional elevation; Fig. 3 a plan of Fig. 2; 25 Fig. 4 a detached perspective view showing the connections at one side; Fig. 5 a similar view showing connections at the other side; Fig. 6 a view illustrating a construction where the connections between the 30 rails and apron are rigid.

The device is adapted for attachment to vehicles having tops A with overhanging hoods B, and consists essentially of two fixed supporting rails C, C, and connections 35 D, D, which are supported by said rails and slide thereon and each of which is attached to the apron or shield E adjacent to one side thereof. These connections D, D may be flexible, as shown in Figs. 1, 2, 3 and 4, or 40 they may be rigid, as in Fig. 6, but in any case one of the said connections slides upon one of the rails back and forth but is permanently attached thereto so as to constitute a permanent connection of the apron with the 45 supporting rail, while the other connection slides upon its rail but may be disconnected from the latter or, what is the same, from the apron.

The rails C, C, are attached generally each 50 at one end beneath the overhanging hood and at the other end to the adjacent side of the vehicle top in such position as to properly support the connection and the apron beneath the hood and permit either connection 55 to slide forward when the driver desires to get into or out of the vehicle, while both

connections may be carried back to the position shown in Fig. 2 when the driver is to be protected in driving.

The apron may be of any suitable character with any of the usual openings or means for permitting the passage of the reins.

In order to secure a greater length of sliding movement I prefer to arrange the supporting rails so as to converge at the 65 outer ends, or diagonally, beneath the hood and the permanent attachment of one of the connections with the rail may be through the medium of a closed link 2, Fig. 4, or any other suitable character of slide which will 70 slide on but cannot be removed from the rail, while the detachable connection may be in the form of a snap-hook 3, which may be either applied to the rail itself, as in Fig. 1, or to an eye 4 upon the apron, as in Fig. 5. 75 Preferably the connections are flexible, in the form of straps, or chains, but each connection may be the end of a rod or bar 7 which extends through a suitable hem at the top of the apron, one of the ends being 80 hooked for detachable connection with the supporting rail and the other being formed in a closed eye as shown in Fig. 6.

Whatever may be the form and arrangement of the connections, one of them being 85 permanently connected with the supporting rail while permitting necessary sliding movements prevents the apron from being removed and lost or injured. A further advantage of the combination above set forth is that the 90 apron may be made into a roll by rolling it up from the bottom and then swinging it upward beneath the top A and connecting it in that position. Preferably the adjustment may be made by detaching one of the connections and swinging the rolled apron to one side beneath the top, as shown in Fig. 2, and securing it in that position by means of a strap or support F which, as shown, is fastened at the end to the top and provided at 100 the other with a hook for engaging an eye upon the top.

Preferably the apron will be better supported if it is provided with a cross-bar 7 at the upper edge which not only stiffens it and 105 tends to keep it in shape and prevents sagging under the action of the wind, but also affords a better attachment for the connections D, and, as shown in Fig. 6 where the connections are rigid, this cross-bar may be 110 part of the connections themselves.

For the purpose of better attaching the

supporting rails to the vehicle I prefer to provide each at the outer end with one or more openings x for screws for connecting to the hood and with an elongated slot y at the inner end for screws passing into the side of the vehicle top so that the rails may be attached at such point as the construction of the vehicle top will best require.

While I have shown the apron as permanently connected to a slide sliding upon a fixed rail or support it will be evident that it may be permanently connected to the end of the sliding rail in that class of devices where sliding rails are used so as in both cases to be a permanent fixture to the vehicle.

I do not here claim broadly the combination of the flexible curtain and supports permitting the curtain to be swung to one side and rolled and secured in an elevated position, as the same is the subject of a separate application Serial No. 464001.

Without limiting myself to the precise construction and arrangements of parts, I claim as my invention:

25 1. The combination with the hood and

apron of a vehicle, of rails fixedly supported beneath the hood, and a connection between the apron at each side and one of the rails, each of the said connections supported to slide upon the rail and one of the said connections being detachable to permit the apron to be swung to one side towards the side of the vehicle and means for supporting the apron when rolled and swung to said side.

2. The combination with the hood of a vehicle, of fixed supporting rails, a storm apron, a permanent flexible but sliding connection between the apron at one side and one of said rails, a detachable sliding connection between the apron and the other rail, and means for supporting the apron beneath the top of the vehicle and at one side when said apron is rolled and swung beneath said top.

In testimony whereof I affix my signature in presence of two witnesses.

EDWARD A. HERR.
